PIANO ACTION

Benjamin F. Miessner, Morristown, N. J.

Application December 7, 1944, Serial No. 566,979

9 Claims. (Cl. 84—240)

1

The invention relates to piano actions and has for its object to provide a piano action of novel construction in which provision is made for arresting rebound of the hammers during the playing of the instrument, to prevent unintentional impacting of the strings or other vibrators thereby.

The invention contemplates further a rebound suppression means of reduced mass and compact structure and efficient operation.

A further object of the invention is to provide a novel piano action of the indicated type, in which the speed of repetition for rapid playing is not affected by the means for suppressing the rebound of the hammers.

In addition, the invention has for its object to simplify the construction and arrangement of the novel piano action.

Other objects will appear from the description hereinafter, and the features of novelty will be pointed out in the claims.

In the accompanying drawings which illustrate an example of the invention without defining its limits,

Fig. 1 is an elevation illustrating the novel action;

Fig. 2 is a fragmentary enlarged view of the rebound suppression means; and

Fig. 3 is an oscillogram diagrammatically illustrating the operation of the novel piano action.

In the form illustrated in Fig. 1, the reference numeral 1 indicates the key bed which constitutes a part of the piano case in the conventional manner, and supports the key frame 2 on which the key 3 is pivotally mounted on the balance pin 4 and pad 5. A guide pin 6 and pad 7 are provided in the customary manner at the forward striking end 3—a of the key 3. At its rear end, the key 3 is continued in the form of a downwardly extending, preferably inclined, arm 3—b provided near its free end with an inserted plug 8 of lead or other metal to constitute a weight at this point, said arm 3—b normally resting on a pad 9 suitably secured in surface engagement with a rail 10 conveniently mounted in the case of the piano.

The key is further provided with a capstan screw 11 projecting perpendicularly to the arm 3—b, and carried thereby at a predetermined point, for co-operation with the hammer as will appear more fully hereinafter. A screw-eye 12 or equivalent device depends from the lower end of the arm 3—b as illustrated in Fig. 1.

The hammer comprises a felt head 13 mounted on the stem 14 which in turn is carried by the

2

butt 15 pivotally mounted at 16, upon the flange 17 fastened by means of a screw 18 upon the rail 19 suitably mounted in the instrument. The butt 15 is provided with a pad 15—a which is suitably secured to said butt 15, the latter further including a second pad 15—b located beneath the pad 15—a for the purpose of silencing noises which otherwise would develop at this point. The rail 19 carries a pad 20 located in the path of movement of the key-arm 3—b and acting as a stop for the upward movement of the arm 3—b when the key 3 is operated. A hammer spring 21 is mounted on and depends from a rail 22 suitably supported in the piano and has its free end in contact with the butt 15 of the hammer as shown. A pad 23 is suitably fixed in surface engagement with the rail 22 to act as a stop for the damper as will more fully appear hereinafter.

The damper head 24 is attached by means of a set screw 25 to a damper rod 26 which in turn is carried by the wooden damper lever 27 influenced by a preferably wire spring 28, and pivoted at 29, on a flange 30 which is attached to the rail 19 by means of a screw 31.

The damper head 24 is operated by the key 3 through the medium of a floating link or push-rod 33, threaded at its opposite ends, and carrying preferably wooden buttons 34 provided with suitably-attached felt pads 35, and tubular noise silencing rubber or other sleeves 36, as illustrated. The push-rod 33 extends through the screw-eyes 12 and 32 or their equivalent, with the buttons 34 and pads 35 located upon the opposed or facing sides of the respective screw-eyes 12 and 32, and the sleeves 36 located in the insides thereof, as illustrated. Screw-threaded adjustment of the wooden buttons 34 on the threaded push-rod 33 serves to selectively adjust the motion and action of the damper. The piano string 37 or other vibrator may be mounted in the instrument in the conventional manner so as to be capable of being struck by the hammer 13, and damped by the damper 24.

The hammer is provided with a guide rod 38 preferably of Duralumin, and including a head 39 at its free end and a contiguous visco-elastic pad 40 mounted on said rod 38, in any convenient manner. This Duralumin guide rod is preferably electroplated with a coating of non-oxidizing metal such as chromium to maintain low sliding friction for the weight 41 slidably mounted on the rod 38, which also carries a compression spring 42 surrounding said rod 38 between the weight 41 and the hammer, as illustrated in Figs. 1 and 2. In the preferred arrangement, the guide rod

23 is set into a rubber bushing 43 countersunk into the wooden tail of the hammer, and secured therein in any suitable manner, as by gluing, the arrangement being such that said bushing 43 projects outwardly beyond the wooden tail of the hammer as shown.

The spring 42 is of a diameter at its hammer end to fit securely upon the protruding end of the rubber bushing 43 and gradually increases in diameter toward its mid-section and then tapers to a smaller diameter in a direction toward the weight 41. In other words, the spring 42 tapers in opposite directions from an enlarged mid-section so that when said spring 42 is fully compressed, its length is relatively small. The right-hand end of the spring 42 in Fig. 1, fits snugly about the guide rod 38 to prevent vibratory noises, and at the same time, is arranged to slide freely along the guide rod 38 when struck by the weight 41, in the operation of the piano action.

The weight 41 preferably is provided with a noise-silencing leather or other bushing 41-a impregnated with graphite as a lubricant, to facilitate the sliding movements of said weight 41, lengthwise of the guide rod 38. Preferably, a relatively thin rubber washer 47 is also located between the pad 40 and the weight 41, to avoid and silence slapping noises otherwise developed, when the weight 41 strikes the pad 40. The latter, in its preferred form, consists of a visco-elastic synthetic material having high viscosity and low elasticity such as a synthetic resin having these properties. To prevent "cold flow" of this material, it may be dipped in liquid rubber to coat it with a thin film of rubber 40-a, and when this rubber film is dry, and the pad 40 has been cemented or otherwise secured to the head 39 of the guide rod 38, the entire pad 40 may be dipped in flake graphite, which is rubbed into the rubber to prevent stickiness. For visco-elastic pads which develop no slapping noise when impacted by the weight 41, the rubber washer 47 may be omitted, and for pad material which is not subject to "cold flow," the rubber film may also be omitted. Furthermore, for non-sticking pad material, the graphite coating may be omitted.

The hammers normally rest against a pad 48 suitably mounted in surface engagement with a rail 49, which, by conventional means not shown, may be shifted at will to the left in Fig. 1, so as to shorten the hammer stroke for "soft-pedal" operation. The pad 48 may also be made of visco-elastic material to suppress rebound of the hammer from said pad for strong, quickly-released key blows. For such key blows, in conventional actions, the hammer, especially of the heavy, bass type, is capable of rebounding back to the string and re-striking the same, which objection is avoided by the use of the visco-elastic pad 48 instead of the customary felt.

The dampers 24 are also controlled by means of a conventional "loud pedal" lifter, not shown, which, by pushing all of the damper rods at their lower ends to the left, disengages all dampers from the strings 37, independently of the key control of said dampers.

In operation, when the key 3 is struck at its playing end 3-a, the capstan screw 11 exerts a pushing force against the pad 15-a, to thereby cause the hammer 13 to be moved toward the string 37 or other vibrator. The capstan screw 11 remains in contact with the hammer until the latter reaches a point about $\frac{1}{4}$ of an inch from its associated string 37, at which point the key 3 and its arm 3-b come to rest against the pads

7 and 20, respectively. At this stage, the hammer continues its movement onward under its own momentum, and strikes the string 37 or other vibrator, from which the hammer rebounds back into contact with the capstan screw 11 through the pad 15-a.

The weight 41 is accelerated with the hammer, being driven by the pad 40 and guide rod 38 carried by said hammer.

When the hammer head 13 strikes the string 37 or other vibrator, and the hammer begins to lose forward velocity, the weight 41 starts to slide lengthwise of the guide rod 38 toward the spring 42, and as the hammer rebounds in the reverse direction from the string 37 or other vibrator, the weight velocity on the guide rod 38 increases. As the hammer head 13 is about to leave the string 37 or other vibrator, the weight 41 begins to compress the spring 42, the amount of such compression varying with the force of the key blow.

As the spring 42 is thus compressed, it develops an opposing force against the hammer which somewhat reduces the velocity of the hammer toward the capstan screw 11. Part of the kinetic energy of the weight 41 is therefore utilized to slow down the velocity of the hammer as the latter rebounds from the string 37 or other vibrator, and a part of said energy is stored in the spring 42 as potential energy.

The hammer continues onward in its return movement, strikes the capstan screw 11 (when the key 3 is held down) deflects the stem 14 and compresses the pads 5, 15-a, and 15-b. Then, as the hammer starts to rebound back toward the string 37 or other vibrator, the weight 41 is driven by the compressed spring 42 against the rubber washer and visco-elastic pad 40 on the guide rod 38, with just the right amount of force to neutralize the tendency of the hammer to rebound toward the string 37.

I have found that, with leather or felt pads at 5, 15-a, and 15-b, the weight of the element 41 should be 0.2 times the weight of the associated hammer, as measured with the hammer stem 14 horizontal and the hammer flange 17 fixed, as in a vise.

The oscillogram illustrated in Fig. 3 shows diagrammatically, the hammer motion with the instant improved and novel anti-rebound attachment.

The hammer leaves its normal position of rest on the pad 43 of the back rail 49, as the key 3 is struck, and gains velocity until the driving motion of the key 3 is stopped by the pads 7 and 20 when the curve crosses the line A. Thereafter, the hammer continues its motion until it strikes the string 37 or other vibrator where the curve crosses the line B. The hammer then slows down, comes to a stop at C, and reverses its direction of movement back to the capstan screw 11, which it recontacts as the curve recrosses the line A. When the key 3 is held down following the key blow, the capstan screw 11 remains in fixed position corresponding to the line A of the hammer curve. The hammer, therefore, strikes the capstan screw 11 through the intervening pad 15-a, and, due to compliances in the hammer stem 14, pads 15-a, 15-b, and 5, and elsewhere in the key assembly, the hammer deflects back to the point D in the curve, after which it again reverses its motion toward the string 37 or other vibrator. Just as the hammer is about to leave the capstan screw 11 at point F of the curve, the weight 41, impelled by the spring 42, strikes the rubber

washer 47 and pad 40, and thereby brings the hammer to rest upon and in engagement with the capstan screw 11.

In cases where the key 3 is not held down following the key blow, as in rapid repetition, the hammer continues on backward from the string 37 or other vibrator, along the dotted line until it recontacts the capstan screw 11 or the pad 48 on the back rail 49.

In this case, the weight 41 strikes the pad 40 while the hammer is moving in the same direction, and thus somewhat accelerates the return motion of said hammer back to its normal position. In this manner, the speed of repetition of the hammer is unimpaired by the anti-rebound attachment of the guide rod and weight assembly.

The operation of the anti-rebound means is effective at all hammer velocities due to the fact that the spring 42 regulates the effective forward and rearward stroke of the weight 41. This stroke or travel distance, is largest for high hammer velocities and smallest for lowest hammer velocities, the velocity of the weight 41 being equal to the hammer velocity for all key blows of every strength.

The amount of kinetic energy required in the weight 41 to neutralize the kinetic energy of the hammer and bring it to rest without rebounding back to the string 37 or other vibrator, is considerably lower than that required to effect this operation in the manner disclosed in my co-pending application, Serial No. 556,166, filed September 28, 1944. This is due to the fact that considerable of the residual kinetic energy in the hammer, after it leaves the string or other vibrator, is dissipated in the various compliances during its rearward deflection after recontacting the capstan screw. The velocity of the hammer as it begins to leave the capstan screw in a return movement toward the string, is, therefore, considerably lower than its velocity on leaving the string. Since its kinetic energy is proportional to the square of its velocity, this reduction in its velocity before neutralization by the loose weight 41, is important in reducing the amount and dimensions of this loose weight 41 necessary for efficient operation.

The reduction in the velocity of the hammer at the point F of the curve in the oscillogram of Fig. 3, just before the weight 41 strikes the pad 40, may be increased by choosing, for the pads 15-a or 15-b or for both of these on the hammer butt 15, suitable material having viscous damping properties which will still further absorb kinetic energy from the hammer. This makes possible a still further decrease in the weight of the mass 41, required to prevent rebound of the hammer back towards the string 37 or other vibrator.

In the same manner, the pad 5 beneath the key 3 on the balance rail pin 4, may also be made of visco-elastic material since this pad 5 is compressed when the hammer strikes the capstan screw 11. It will also assist in absorbing kinetic energy from the hammer so as to reduce the amount thereof requiring neutralization.

I have found that by the use of these visco-elastic pads at 5, 15-a, and 15-b, the hammer velocity is so much reduced as the hammer begins to rebound from the capstan screw back to the string, that the weight of the loose mass represented by the weight 41, may be reduced to approximately 13% or less of the weight of the hammer with its stem horizontal and its flange fixed in a support, as against a 21% weight of

loose mass with conventional leather and felt pads. To prevent "cold flow" of these pads when the latter are subject to such flow, said pads may be encased in a thin rubber skin or film by dipping them in rubber, drying, and covering with graphite. If the pads 5, 15-a, and 15-b are sufficiently effective to absorb all the residual kinetic energy of the hammer for maximum strength of key blow so as to prevent hammer rebound from the capstan screw back to the string, the anti-rebound attachments 38, 39, 40, 41, 42, and 47 may be omitted.

I have found that the guide rods 38 may be of the same length for all hammer sizes and that the springs 42 may be of the same size and stiffness for all hammer sizes. The purpose of the rubber bushing 43 is to prevent the shock impulse, set up by the weight 41 when striking the pad 40, from being communicated to the hammer head 13 and through its stem 14 and flange 17 into the structure of the piano from which it radiates as an impact noise.

Although the present invention has been described in conjunction with a preferred embodiment, it is to be understood that modifications and variations may be resorted to without departing from the spirit and scope of the invention, as those skilled in the art will readily understand. For instance, the sliding or suppression weights 30 may be replaced by loose masses of granular, solid, or liquid type contained in a tubular part of or attachment to the hammer. Such variations and modifications are considered to be within the purview and scope of the claims:

I claim:

1. In a musical instrument of the piano type, a vibrator, a hammer movably mounted in striking relation to said vibrator, a movably mounted operating key, actuating means operated by said key effective on said hammer to cause the latter to strike said vibrator, a rebound suppressing weight associated with said hammer and movable relatively thereto, and a spring co-operating with said weight to reduce the velocity of the return movement of the hammer from the vibrator, and to neutralize rebound of said hammer relatively to said actuating means upon the return of the hammer thereto subsequently to its impact against said vibrator.

2. In a musical instrument of the piano type, a vibrator, a hammer movably mounted in striking relation to said vibrator, a movably mounted operating key, actuating means operated by said key effective on said hammer to cause the latter to strike said vibrator, guide means carried by said hammer and extending in the direction of its operative movements, a rebound suppressing mass movable relatively to said guide means as said hammer is operated, and a spring acted on by said mass to reduce the velocity of the return movement of the hammer from the vibrator, and to neutralize rebound of said hammer relatively to said actuating means upon the return of the hammer thereto subsequently to its impact against said vibrator.

3. In a musical instrument of the piano type, a vibrator, a hammer movably mounted in striking relation to said vibrator, a movably mounted operating key, actuating means operated by said key effective on said hammer to cause the latter to strike said vibrator, a guide rod carried by said hammer and extending in the direction of its operative movements, and a rebound suppressing means including a weight slidably lengthwise of said rod for reducing the velocity of the return

movement of the hammer from the vibrator, and for neutralizing rebound thereof relatively to said actuating means upon the return of the hammer thereto subsequently to its impact against said vibrator.

4. In a musical instrument of the piano type, a vibrator, a hammer movably mounted in striking relation to said vibrator, a movably mounted operating key, actuating means operated by said key effective on said hammer to cause the latter to strike said vibrator, a guide rod carried by said hammer and extending in the direction of its operative movements, a rebound suppressing weight externally carried by and slidably mounted on said rod, a head carried by said rod in the path of movement of said weight in one direction, and a rebound suppressing spring carried by said rod in the path of movement of said weight in the opposite direction, and arranged to be compressed thereby to reduce the velocity of the return movement of the hammer from the vibrator, and to force said weight against said head to neutralize rebound of said hammer relatively to said actuating means subsequently to its impact against said vibrator.

5. In a musical instrument of the piano type, a pad of visco-elastic, energy-absorbing material, and an elastic film encasing said pad and having sufficient resiliency to allow said pad to deform under pressure and to restore said pad to its normal shape when the pressure is relieved.

6. In a musical instrument of the piano type, a pad of visco-elastic, energy-absorbing material, and a rubber skin encasing said pad and having sufficient resiliency to allow said pad to deform under pressure and to restore said pad to its normal shape when the pressure is relieved.

7. In a musical instrument of the piano type, a vibrator, a hammer movably mounted in striking relation to said vibrator, an operating key in operative association with said hammer to cause the latter to strike said vibrator, a rail, and a pad of visco-elastic material on said rail against which said hammer normally rests and to which it returns subsequently to its impact against the vibrator, said pad suppressing rebound of said hammer therefrom subsequently to said return thereto.

8. In a musical instrument, an exciting action for a vibrator comprising, in combination, a hammer movable to strike the vibrator; actuating means for moving the hammer and against which the hammer rebounds after striking the vibrator; means, rendered effective by the striking of the vibrator by the hammer, for storing kinetic energy in potential-energy form during the rebound of the hammer from the vibrator; and means rendering the stored energy effective to oppose a rebound of the hammer from the actuating means.

9. In a musical instrument, an exciting action for a vibrator comprising, in combination, a hammer movable to strike the vibrator; actuating means for moving the hammer and against which the hammer rebounds after striking the vibrator; a mass moved by said actuating means coincidentally with the movement of the hammer by the actuating means, and movable relative to the hammer; resilient means regulating the motion of said mass relative to the hammer upon the striking of the vibrator by the hammer; and means, forming a portion of the hammer, against which said mass delivers an impact when the hammer has rebounded against the actuating means.
